UNITED STATES PATENT OFFICE

JOHN F. TARRIS, OF CLYDE, OHIO

TIGHTENER FOR CONCRETE FORM TIE WIRES

Application filed December 18, 1930. Serial No. 502,837.

This invention relates generally to concrete forms and more particularly to a device for tightening the tie wires of the forms and has for its primary object to provide, in a manner as hereinafter set forth, a device of this character embodying the novel construction and arrangement of parts whereby tie wires may be tightened to the desired tension in an expeditious manner and secured under tension as long as desired.

Other objects of the invention are to provide a tightener for concrete form tie wires of the character described which will be simple in construction, strong, durable, efficient and reliable in use and which may be manufactured at low cost.

All of the foregoing and still further objects and advantages of the invention may become apparent from a study of the following specification, taken in connection with the accompanying drawing wherein like characters of reference designate corresponding parts throughout the several views, and wherein:

Figure 1 is a view in vertical section showing the device in accordance with this invention mounted in position on a concrete form.

Figure 2 is a view in front elevation showing a pair of the devices mounted in position on the studding of a concrete form.

Figure 3 is a sectional view taken substantially on the line 3—3 of Figure 2.

Figure 4 is a view in perspective of one of the clamping wires.

Referring to the drawing in detail, it will be seen that the reference numeral 1 designates generally a portion of a concrete form for the reception of concrete, said form including the studding 2. Tie or clamping wires 3 are bent to substantially U-shaped form and inserted through holes provided therefor in the concrete form 1 in a manner to straddle or embrace the studs 2 which are disposed on opposite sides of the concrete form. The free ends of the tie or clamping wires 3 project beyond the adjacent stud 2 of the concrete form for a reason to be presently set forth.

A bracket designated generally by the reference numeral 4 is adapted for disposition

against the outer face of the studs 2 which is disposed between the free end portions of the tie or clamping wires 3 and said bracket includes a flat base portion 5 from which extend the spaced, opposed, integral arms 6 having horizontally aligned openings 7 therein. The bracket 4 further includes an upper wall or plate 8 having a vertical opening 9 therein in which is operable a pawl or dog 10 having a head 11 formed integrally on its lower end.

An elongated, tubular bar 12 extends rotatably through the openings 7 in the arms 6 of the bracket 4 and has fixed on an intermediate portion thereof for rotation therewith between the arms 6 a ratchet 13 which, if desired, may be formed integrally with the tubular bar 12. Suitable means may be provided for retaining the tubular bar 12 against sliding movement in the openings 7, such as a transverse cotter pin 14. The tubular bar 12 is further provided with spaced transverse openings 15 on opposite sides of the bracket 4 for the reception of the end portions of the tie or clamping wire 3 and said tubular bar is still further provided, on one end, with a polygonal head 16 for engagement by a suitable actuating tool such as a wrench for rotating the tubular bar.

In use, the tie or clamping wires 3 are inserted through the holes provided therefor in the concrete form 1 in the usual manner, and in which position said wires straddle the studs 2. The free end portions of the tie or clamping wires are then inserted through one of the openings 15 on each side of the bracket 4 with said bracket 4 held against the outer side of one of the studs in the manner clearly illustrated in the drawing. A wrench is then applied to the polygonal head 16 and the tubular bar 12 is manually rotated to wind the end portions of the tie or clamping wires 3 thereon and thus tighten said wires to the desired tension. When the tubular bar 12 is rotated in a direction to tighten the tie or clamping wires, the pawl or dog 10, which is gravity actuated, will ride over the ratchet teeth but the head 11 of said pawl or dog will engage the ratchet teeth in a manner to prevent retrograde rotation of

the tubular bar 12, as will be readily apparent. As hereinbefore indicated, the pawl or dog 10 is mounted for vertical sliding movement in the opening 9 in the upper wall or plate 8 of the bracket 4. The head 11 is provided with flat front and rear sides, the front side engaging one side of a ratchet tooth and the rear side being in abutting engagement with the base portion 5 of the bracket 4 when the pawl or dog 10 is in operative position. In this manner the pawl is supported against lateral pressure exerted thereon by the ratchet on the bar 12.

It is believed that the many advantages of a device in accordance with this invention will be readily understood, and although the preferred embodiment of the invention is as illustrated and described, it is to be understood that changes in the details of construction may be had which will fall within the scope of the invention as claimed.

What is claimed as new is:—

A device of the class described comprising a bracket, a ratchet rotatably supported by the bracket, said bracket having a vertically arranged part spaced from the ratchet and a top part extending over the space between the vertical part and the ratchet, said top part having an opening therein, a gravity actuated pawl of substantially inverted T-shape having its stem passing slidably through the opening with one end of its head slidingly engaging the vertical part and its other end engaging the teeth of the ratchet.

In testimony whereof I affix my signature.
JOHN F. TARRIS.
